Attorney.

UNITED STATES PATENT OFFICE.

HUGO SCHICK, OF ST. LOUIS, MISSOURI.

COMBINATION BACKING AND POST FOR ARTIFICIAL ANTERIOR TEETH.

1,383,030.

Specification of Letters Patent. Patented June 28, 1921.

Application filed July 21, 1919. Serial No. 312,192.

To all whom it may concern:

Be it known that I, Hugo SCHICK, a citizen of the United States, residing in the city of St. Louis and State of Missouri, have invented certain new and useful Combination Backings and Posts for Artificial Anterior Teeth, of which the following is a specification.

My invention relates to a combination backing and post for artificial anterior teeth crowns, and has for its object to provide a combined backing and post for use in connection with what is known as Steel's facings, the use of which backing and post will permit a dentist to do all fitting in a patient's mouth and thereby facilitate manipulations in the making of all styles of Richmond crowns, as no impressions and bite are necessary as required with the present type of backing.

With the above and other objects in view, the invention consists in the improvements which I will now describe in the following specification and finally point out in the claims.

Referring to the accompanying drawings forming a part of this specification wherein like characters of reference denote similar parts throughout the several views:

30 Fig. 1, is an enlarged side elevation of a crown made with my improved combination backing and post.

Fig. 2, is a partly sectional elevation thereof.

35 Fig. 3, is a rear elevation thereof.

Fig. 4, is a front elevation thereof.

Fig. 5, is an enlarged side elevation of the combination backing and post.

Fig. 6, is a plan view of the blank for 40 forming the inlay and post for the backing.

Fig. 7, is a side elevation of the inlay and post after it has been formed and prior to being fixed to the backing.

Fig. 8, is a horizontal section taken on line 45 8—8 of Fig. 1.

Fig. 9, is a top plan view of the combination backing and post.

Fig. 10, is a front elevation of the combination backing and post.

50 Fig. 11, is a rear elevation thereof.

Fig. 12, is a perspective view of a facing.

Referring to the drawings the reference character 1 designates a natural tooth root which is provided with a suitable cap 2. 3

55 represents an artificial tooth facing. The facing 3 is provided with a suitably shaped

vertically disposed socket 4 communicating with the cervix or upper face 5 of the facing 3. The facing 3 is further provided with a narrow channel 6 which communicates on 60 one side with the rear face 7 of the facing 3 and on the other with the socket 4.

In carrying out the aim of my present invention, the combination backing and post consist, essentially of a suitable metallic 65 backing, an inlay and a root-post.

The backing is designated 8 and consists of a suitable metallic plate provided with a suitable opening 9.

The inlay consists of a preferably tubular 70 head, or body 10, a neck, or fin 11 integral with the head or body 10, and stud 12 integral with the neck or fin 11. The stud 12 is adapted to engage in the opening 9 of the backing 8 and is securely fixed thereto by 75 riveting the same for securely holding the inlay in position.

The root-post consists of a suitable shaped extension 13 of the neck or fin 11, as clearly shown in Figs. 6 and 7. The root-post is 80 preferably tapered, and when formed will be substantially flat, as shown in Fig. 9, or it may be expanded to form a hollow cone shaped post, as is manifest.

In forming the device from the blank 85 shown in Fig. 6, it is necessary to bend portion 10' of the blank into the tubular head or body 10, of the inlay and cause the side portions 11' of the blank to engage one another to form the neck or fin 11, as clearly 90 shown in Fig. 5. In bringing the side portions 11' of the blank together, the ears 12' thereof, are at the same time brought together to form the stud 12. The post blank 13' being integral with one of the side portions 11' is also bent back upon itself and forms the root-post simultaneously with the forming of the neck, or fin 11 and the stud 12. The lower edge 14 of the root-post 13, may, if desired, be soldered, as at 15, or 95 otherwise secured to the backing 8 to add rigidity to the tooth-post 13.

The inlay only extends downward a short distance below the upper edge of the backing 8 and extends upwardly therefrom any 100 suitable distance in the form of a root-post 13.

The tubular head, or body 11 of the inlay is adapted to engage in the socket 4 of the facing 3 from the cervix toward the biting 110 edge of the facing 3, as clearly shown in Fig. 2, and the neck, or fin 11 engages in

the channel 6 of the facing 3, as shown in Fig. 8.

After the cap, backing and post, and the facing have been fitted to the root 1, they 5 are held together with sticky wax, removed from the mouth, soldered and polished and the facing is then cemented in position upon the inlay.

The many advantages of the herein de- 10 scribed combination backing and post will readily suggest themselves to those skilled in the art to which it appertains.

What I claim is:

1. A combined backing and post for arti- 15 ficial anterior teeth, comprising a backing- plate, an inlay fixed to the face of said back- ing-plate and a root-post extending up- wardly from said backing-plate.

2. A combined backing and post for arti- 20 ficial anterior teeth, comprising a backing- plate, an inlay fixed to the face of the back- ing-plate and extending below the upper edge of the plate a suitable distance, and a root-post integral with the inlay.

25 3. A combined backing and post for arti-

ficial interior teeth, comprising a backing- plate, an inlay fixed to the face of the back- ing-plate and extending below the upper edge of the plate a suitable distance, means 30 uniting the tubular head of the inlay with the backing-plate, and a root-post integral with the inlay.

4. A combined backing and post for arti- 35 ficial anterior teeth, comprising a backing- plate, a laterally projecting inlay fixed to 35 said plate, and a root-post integral with the inlay extending upwardly from the upper edge thereof.

5. An artificial tooth, comprising a por- 40 celain facing having a recessed socket ex- tending from the cervix toward the biting edge thereof, a backing-plate, an inlay fixed to the facing engaging in the recessed socket, and a root-post integral with the inlay ex- 45 tending upwardly above the upper edge of the backing-plate.

In testimony whereof, I have hereunto signed my name to the specification.

HUGO SCHICK.
